(57) **CLAIM**

I claim the ornamental design for a shoe sole, as shown and described.

DESCRIPTION

FIG. 1 is a top-plan view of the shoe sole embodying my new design;

FIG. 2 is a bottom-plan view thereof;

FIG. 3 is a medial side-elevational view thereof;

FIG. 4 is a lateral side-elevational view thereof;

FIG. 5 is a front elevational view thereof;

FIG. 6 is a rear-elevational view thereof;

FIG. 7 is a bottom perspective view thereof;

FIG. 8 is a cross-sectional view taken along the line 8—8 of FIG. 2;

FIG. 9 is a cross-section of the shoe sole taken at line 9—9 of FIG. 8;

FIG. 10 is a cross-sectional view of the shoe sole taken at line 10—10 of FIG. 8;

FIG. 11 is a cross-sectional view of the shoe sole taken at line 11—11 of FIG. 8;

FIG. 12 is a cross-sectional view of the shoe sole taken at line 12—12 of FIG. 8;

FIG. 13 is a cross-sectional view taken along the line 13—13 of FIG. 8; and,

FIG. 14 is a cross-sectional view taken along the line of 14—14 of FIG. 8.
